Primary Examiner — Melanie H Tung*Assistant Examiner* — Fitzgerald L Butac(74) *Attorney, Agent, or Firm* — Quickpatents, LLC;
Kevin Prince(57) **CLAIM**

I claim the ornamental design for a weight scale, as shown and described.

DESCRIPTION

FIG. 1 is a perspective view of a weight scale, showing my new design:

FIG. 2 is a top plan view of FIG. 1;

FIG. 3 is a bottom plan view of FIG. 1;

FIG. 4 is a right-side elevational view of FIG. 1;

FIG. 5 is a left-side elevational view of FIG. 1;

FIG. 6 is a front elevational view of FIG. 1; and,

FIG. 7 is a rear elevational view of FIG. 1.

The broken lines in the drawings depict portions of the weight scale that form no part of the claimed design.
